UNITED STATES PATENT OFFICE.

JOHN D. NIES, OF ST. CHARLES, ILLINOIS, ASSIGNOR TO KIMBLE ELECTRIC COMPANY, OF CHICAGO, ILLINOIS, A CORPORATION OF ILLINOIS.

BRUSH MOUNTING.

Application filed April 27, 1921. Serial No. 464,844.

To all whom it may concern:

Be it known that I, JOHN D. NIES, a citizen of the United States, residing at St. Charles, in the county of Kane and State of Illinois, have invented certain new and useful Improvements in a Brush Mounting, of which the following is a specification.

This invention pertains in general to electrical devices, and more specifically has to do with a novel mounting for current-conducting brushes.

The main and primary objects of the invention, broadly stated, are the provision of an improved brush mounting wherein the brush, its holder and its regulator are carried on a unitary supporting block of insulating material; wherein the said regulator, although in contact with the brush, is insulated at all other points, thus preventing any leakage of current through the same and consequent arc-pitting of its relatively moving parts; wherein the cable attaching means efficiently serve both to hold the wire ends securely and to prevent the insulating fabric covering of the cable from being drawn back away from said ends, and wherein the construction of the mounting enables the same to be fitted to motor frames of various sizes, whereby the necessity and expense of making a different supporting block for each size of frame is obviated.

Another important object of the invention is the provision in such a mounting of a brush regulator which is adapted to exert a substantially constant pressure on the brush regardless of the changing position thereof and which is cooperatively associated with the supporting block in such a manner as to permit ready adjustment of the pressure applied to the brush thereby.

Other objects and advantages of the present invention will become apparent as the nature of the same is better understood from the following description and accompanying drawing wherein one embodiment of the invention is set forth for the purpose of exemplification. The invention is obviously susceptible of embodiment in forms which differ in unessential details from that here illustrated and described, and it should therefore be understood that this particular embodiment is not intended to restrict the spirit of the invention or to limit unnecessarily the scope of the appended claims.

In the drawings,

Fig. 1 is a front elevation of the brush mounting of this invention;

Fig. 2 is a section on the line 2—2 of Fig. 1, illustrating among other things the manner of attachment of the block to the motor frame;

Fig. 3 is a top plan view of the mounting;

Fig. 4 is a fragmentary section through the brush regulator and that portion of the block carrying the same;

Fig. 5 is a fragmentary front elevation of the mounting, showing in section the brush, brush-holder and pin on which the regulator is carried;

Fig. 6 is a rear elevation of the mounting, illustrating primarily the cable attaching means and the block construction whereby attachment to various sizes of frames is made possible;

Fig. 7 is a detail view of the regulator cap which adjustably anchors the regulator spring to the block; and

Fig. 8 is a section on the line 8—8 of Fig. 4.

Having reference to the drawing, and more particularly to Figs. 1, 3 and 6 thereof, the numeral 10 designates a block which is molded, or otherwise formed, of insulating material. This block is composed of a slightly arcuate portion 11, and a cylindrical portion 12 disposed, as shown, at one end of said arcuate portion.

A positioning flange 13 is formed on the under side of the arcuate portion near the front face thereof and serves to abut against the end of a motor frame 14 to which the block is fixedly attached by means of a machine screw 15. This screw passes through the block and engages within a threaded radial aperture formed in the periphery of the frame 14. 95

The previously mentioned flange 13 of the block prevents the same from turning about the axis of the screw, and thereby permits a rigid attachment to the frame by means of the one screw. The under supporting surface 16 of the block, as shown in Figs. 2 and 6, is concavely formed on an arc of smaller radius than the radius of curvature of any motor frame to which this mounting is intended to be attached, and will therefore offer a firm support by actually bearing upon the periphery of the motor frame at the ends 17 only of said under surface.

The brush 18 is preferably of the ordinary carbon block type, and is slidably carried 110

in an open ended holder 19 of rectangular cross-section. This holder is provided with a flanged base portion 20 which is set into the insulator block 11 with its outer face 5 flush with the surface thereof. Aligned notches 21 are cut in opposite sides of the holder to expose laterally a smaller and more shallow notch 22 which is disposed in the brush intermediate said notches 21 of the 10 holder. These notches are provided for the purpose of giving the brush regulator, which will be described hereinafter in detail, operative access to the brush regardless of the gradual advancement of the latter 15 towards the commutator (not shown) with which it is cooperatively associated.

A plate 23 is set into the block 11 on that side of the same opposite the holder 19. Machine screws 24 pass through aligned apertures 20 in the plate and block and engage in threaded apertures in the flanged portion 20 of the brushholder, whereby the plate and holder are fixedly secured to the block and an electrical connection formed between the 25 same through said screws. Current conducting cables 25 enter grooves 26 in the surface of the block adjacent the plate, and passing under the edges of the plate are attached to the same at a medial point 30 thereof. In order to attach the wires 27 of the cables to the plate a small ear 28 is cut in the same and bent inwardly. The wire ends are then overlapped on this ear, and the ear pressed outwardly again a sufficient 35 distance to bind the wire ends against displacement. If desired a little solder 28a may then be fused onto the exposed wires to fill the wedge shaped rectangular depression left in the plate and to insure perfect 40 current conduction. The portions of the plate 23 overlapping the fabric covered insulation 29 of the wires 27 adjacent their inner bare ends press inwardly on the cables at these points and prevent withdrawal or 45 fraying of the fabric and insulation ends. It will be evident, of course, that one cable may be attached to the plate 23 in the same manner as described for two.

A direct positive connection is formed between the plate 23 and brush 18 by means of a flexible shunt wire 30 which is attached at 50 one end to the plate by means of an ordinary terminal connecting ring clamped against the same by either of the machine screws 24, 55 and at the other end to the brush by being imbedded in the carbon thereof.

The brush regulator of this invention is carried by the cylindrical portion 12 of the mounting 10. One end of this portion projects forwardly beyond the face of the block 60 to which the brush holder is attached, and terminates just short of a point opposite the notches 21 in the sides of said holder. The cylindrical portion 12 is provided with an 65 axial aperture extending therethrough, and

has its forward end face provided with a plurality of pairs of oppositely disposed radial kerfs 31, as shown in Fig. 5. A cap 32 seats over this slotted end and is provided with two oppositely disposed tongues 70 33 which are adapted to fit into any pair of the kerfs 31 and thereby prevent rotation of the cap relative to the axis of the cylindrical portion of the mounting. This cap, which is best shown in Figs. 4 and 7, is 75 formed on the side thereof opposite the tongues 33 into an axial sleeve portion 34 which is slit longitudinally along one side and there bent tangentially into a lip 35.

The spring 36 of the regulator is of the 80 combined leaf and helical type, being composed of a helical coil 37 disposed on the surface of the cap 32 about the sleeve portion 34 and a leaf portion 38 bent normally outward at the outer end of the coil. The 85 inner end of the spring is formed into a small hook 39 and engages the lip 35 of the sleeve portion of the cap, while the outer end of the spring bears against the bottom of the notch 22 in the brush. A circular 90 housing 40 loosely encompasses the coil of the spring 36 on the cap 32 and is provided at one side with an aperture through which the leaf portion of the spring passes outwardly. 95

A long axial pin 41 passes through a central aperture in the end of the spring housing, through the sleeve portion of the cap and through the axial aperture in the cylindrical portion of the mounting. That end 100 of the pin projecting exteriorly of the spring housing is provided with a transverse cotter 42 to abut against said housing, while the opposite end of the pin projects from the other extremity of the cylindrical portion 12 105 and is there provided with a coaxial spiral spring 43 compressed between two washers 44, the outer of which abuts against a transverse cotter 45 on the pin. This construction serves to maintain the spring housing 110 against the cap, and the latter against the cylindrical portion 12 of the mounting whereby the spring 36 is anchored in a fixed position relative to the mounting 10. If it is desired to vary the pressure exerted by the 115 spring 36 on the brush it is merely necessary to grasp the periphery of the cap, which is knurled for this purpose, draw the same away from the portion 12 until the tongues 33 are free of the kerfs 31, turn the cap in 120 either direction the desired amount, and then release the same and permit the tongues to enter the kerfs with which they are in nearest approximate alignment. Turning the cap in counter-clockwise direction will 125 increase the tension of spring 36, while turning in the opposite direction will decrease the tension. This completes the description of the brush mounting.

It will be noted that the mounting here 130

disclosed is formed as a single insulator block on which the brush holder and brush regulator are both supported. This obviates the necessity of employing insulating sleeves 5 and plates at various points such as are required in the ordinary type metal mounting. Furthermore the regulator spring is insulated at its support, and destructive arc-pitting of the spring and its contiguous 10 current-conducting parts is therefore prevented.

The regulator spring 36, because of its combined helical and leaf construction, exerts a substantially constant pressure on 15 the brush as the latter wears away, rather than the gradually weakening pressure characteristic of ordinary leaf springs when used in this connection.

I claim:

20 1. In a brush mounting, a supporting block, a brush, and a brush regulator acting on the brush to move the same in a straight line, the surfaces of contact between said block and regulator being shaped to permit 25 of selective engagement of one with the other in a number of angular positions.

2. In a brush mounting, a supporting block, a brush, and a brush regulator bearing directly on one end of the brush, the 30 surfaces of contact between said block and regulator being shaped to permit of selective engagement of one with the other in a number of distinct angular positions.

3. In a brush mounting, a supporting 35 block, a brush holder rigidly secured to the block, a brush mounted for reciprocal movement in the holder, a brush regulator comprising a spring adapted to exert pressure on the brush, and adjustable means for connecting the spring to the block.

4. In a brush mounting, a supporting 45 block of insulating material, a brush holder carried by the block, a brush, a brush regulator carried by the block and acting on the brush, means consisting of cooperating portions of the regulator and block for adjusting the pressure exerted by the regulator on the brush, and means for connecting the brush with a current-conducting lead.

5. In a brush mounting, a supporting 55 block adapted to carry a brush and brush holder and having a concave attaching surface on its under side in order to bear at the ends only of such surface upon the convex surface of the object to which attached.

6. In a brush mounting, a supporting 60 block of insulating material adapted to carry a brush, a brush holder and brush regulator, said block having a concave attaching surface on its under side and a contiguous flange at right angles to said surface and along the adjacent face of the flange in order to bear at the ends only of such surface upon the convex surface and end face respectively of 65 the object to which attached, whereby rock-

ing movement of the block in a vertical or horizontal plane is precluded.

7. In a brush mounting, a supporting block, a brush holder carried by said block, a brush, a member in current-conducting 70 connection with the brush, and means for attaching the current-conducting member to a cable whereby to effect indirectly through said member a current-conducting connection of the brush with the cable, said member serving to hold the insulating cover of the cable against withdrawal.

8. In a brush mounting, a supporting block, a brush holder carried by said block, a brush, a member in current-conducting 80 connection with the brush, and means for attaching the current-conducting member to a cable, said member serving to clamp the insulating cover of the cable against the block to prevent withdrawal.

9. In a brush mounting, a supporting block having a groove therein, a brush holder carried by said block, a brush, a member located on said block and partially covering said groove, a current-conducting connection 90 of said member with the brush, a cable occupying said groove, and means for attaching said cable to the member on the under side thereof, said member serving to hold the insulating cover of the cable against withdrawal.

10. In a brush mounting, a supporting block, a brush holder carried by the block, a brush, a brush regulator comprising a spring adapted to bear directly against the brush, 100 and adjustable means for connecting the spring to the block.

11. In a brush mounting, a supporting block, a brush holder carried by the block, a brush adapted in operation to move freely in the holder, a brush regulator carried by the block and comprising a spring adapted to exert pressure on the brush, and adjustable means for connecting the spring to the block.

12. In a brush mounting, a supporting 110 block, a brush holder carried by the block, a brush, a brush regulator carried by the block and comprising a spring adapted to exert pressure on the brush, and adjustable means for connecting the spring to the block, said spring being straight adjacent said brush and helical adjacent said connecting means in order to exert a substantially constant pressure on the brush as it recedes thereunder.

13. In a brush mounting, a supporting 120 block of insulating material, a brush holder carried by the block, a brush, a brush regulator comprising a spring adapted to exert pressure on the brush, and adjustable means for connecting the spring to the block.

14. In a brush mounting, a supporting 130 block of insulating material, a brush holder carried by the block, a brush, a brush regulator carried by the block and comprising a

spring adapted to exert pressure on the brush, and adjustable means for connecting the spring to the block, said spring being helical adjacent said connecting means in order to exert a substantially constant pressure on the brush as it recedes thereunder.

15. In a brush mounting, a brush supporting block adapted for attachment to divers' sizes of electrical machines, said block having a concave attaching face arranged to bear at its extremities only upon the opposed surface of the machine.

16. In a brush mounting, a supporting block, and a brush regulator, one of said elements being provided with a plurality of recesses and the other with a projection adapted to engage selectively in any one of said recesses, whereby to effect and maintain angular adjustment between said elements.

20. 17. In a brush mounting, a supporting block, and a brush regulator pivotally attached thereto, one of said elements being provided with a plurality of recesses and the other with a projection adapted to engage selectively in any one of said recesses, whereby to effect and maintain angular adjustment between said elements.

30. 18. In a brush mounting, a supporting block, a brush regulator pivotally attached thereto, one of said elements being provided with a plurality of recesses and the other with a projection adapted to engage selectively in any one of said recesses, whereby to effect and maintain angular adjustment between said elements, and yielding means serving to hold said projection in inter-engagement with one of said recesses.

40. 19. In a brush mounting, a supporting block having a bore therein and a recessed face at one extremity of said bore, a brush regulator having a bore therein and a projection adjacent one extremity of said bore adapted to engage selectively in any one of said recesses, a coupling member passing through said bores, and yielding means associated with said member and serving to hold said projection in inter-engagement with any one of said recesses.

50. 20. In a brush mounting, a supporting block, and a brush regulator, one of said elements being provided with a plurality of recesses and the other with a plurality of projections, adapted to engage selectively in certain of said recesses, whereby to effect and maintain angular adjustment between said elements.

55. 21. In a brush mounting, a supporting block, and a brush regulator pivotally attached thereto, one of said elements being

provided with a plurality of recesses and the other with a plurality of projections adapted to engage selectively in certain of said recesses, whereby to effect and maintain angular adjustment between said elements.

22. In a brush mounting, a supporting block having a bore therein and a recessed face at one extremity of said bore, a brush regulator having a bore therein and a plurality of projections adjacent one extremity of said bore adapted to engage selectively in certain of said recesses, a coupling member passing through said bores, and yielding means associated with said member and serving to hold said projections in inter-engagement with certain of said recesses. 75

23. In a brush mounting, a supporting block of insulating material carrying a brush holder and brush, a brush regulator mounted on the block, and recesses in the block adjacent the attachment of the regulator for co-action therewith, whereby adjustment of the latter can be effected. 80

24. In a brush mounting, a supporting block of insulating material carrying a brush holder and brush, a brush regulator mounted on the block, and means on the block adjacent the attachment of the regulator for co-action therewith, whereby adjustment of the latter can be effected. 85

25. In a brush mounting, a supporting block of insulating material carrying a brush holder and brush, a brush regulator for the brush mounted on the block, and a shaping of the block adjacent the attachment of the regulator for co-action therewith, whereby adjustment of the latter can be effected. 90

26. In a brush mounting, a brush supporting block having a concave attaching face adapted to bear at its extremities upon an opposed surface of the supporting frame, 100 and means engageable with the block intermediate its extremities for securing the same to the frame.

27. In a brush mounting, a brush supporting block having a concave attaching face 105 adapted to bear at its extremities upon an opposed surface of the supporting frame, and a pin secured to the frame and engageable with the block at a central point thereof for holding the block to the frame. 110

In witness whereof I have hereunto signed my name in the presence of two subscribing witnesses.
